UNITED STATES PATENT OFFICE.

FRANK E. TROUTMAN, OF BUTLER, PENNSYLVANIA.

FURNACE-CHARGING APPARATUS.

1,336,494.

Specification of Letters Patent. Patented Apr. 13, 1920.

Application filed March 5, 1919. Serial No. 280,839.

To all whom it may concern:

Be it known that I, FRANK E. TROUTMAN, a citizen of the United States, a resident of Butler, in the county of Butler and State 5 of Pennsylvania, have invented a new and useful Improvement in Furnace-Charging Apparatus; and I do hereby declare the following to be a full, clear, and exact description thereof.

10 My invention relates to apparatus for charging or filling the pots in glass melting furnaces.

The filling is usually done at present either by shoveling the batch into ladles 15 from small batch wagons, or by having these batch wagons provided with a gate and hoisting the wagons by means of a crane and holding it so suspended, or by attaching the wagon to the furnace over 20 the furnace openings.

This necessitates a great number of small batch receptacles and auxiliary apparatus for hoisting or placing them on the furnace.

25 The ladling is done from the floor and the ladle is moved by hand in and out of the furnace, and to move about the ladling apparatus from one filling position to another is a clumsy and awkward operation.

30 The object of my invention is to provide apparatus by means of which the pots in glass melting furnaces may be quickly and conveniently charged with a minimum amount of labor.

35 To these ends my invention comprises the novel features hereinafter set forth and claimed.

In the accompanying drawing, Figure 1 40 is the side elevation of my improved apparatus, the furnace being shown in section, and the position of the hopper being charged with batch, being shown in dotted lines; Fig. 2 is a plan view showing the parts in charging position with the furnace in 45 section; Fig. 3 is an enlarged plan view of the carriage with the ladle carried thereby broken away; Fig. 4 is a longitudinal section of the ladle housing, and Fig. 5 is an enlarged detail of the switching mechanism.

50 In the drawing the numeral 2 designates an electrically driven trolley arranged to run on the underhung tracks 3 between the girders 4 of a suitable electric crane which spans the furnace room and arranged to 55 travel on the tracks 5. This trolley is also

adapted to run over the tracks 3 to the tracks 6 leading to the batch mixer or storage bin 7 for charging the hopper 8 carried by the trolley 2.

The framework 9 is made up of structural 60 steel work properly braced and trussed to give the requisite strength.

Supported in the frame-work 9 are the tracks 10 and 11 parallel with each other and arranged one above the other. The 65 track 11 is provided with the inclined portions 12 and 13 and the track 10 with the inclined portions 14 and 15 thereby producing an undulating effect. Furthermore the upper track 10 extends beyond the track 11 70 for the purpose more fully hereinafter set forth.

A carriage 16 is adapted to travel on the tracks 10 and 11, the front wheels 17 of said carriage traveling on the upper track 75 10, and the rear wheels 18 traveling on the lower track 11. The rails of the track 11 are provided with rack-bars 19, and the pinions 20 mounted with the rear wheels of said carriage engage said rack-bars. A suitable electric motor 21 is provided on the carriage for advancing and withdrawing same, said motor being connected up with the rear axle to drive the pinions 20.

Mounted on the carriage 16 is the housing 22, said housing being swiveled by the vertical pin 23 secured to said housing and extending up into the sleeve 24 provided with ball-bearings 25. A nut 26 at the upper end of said pin secures the housing in 80 position.

Within the housing 22 is the ladle-shaft 27 fitting in the ball-bearings 28 in said housing. A ladle 29 is carried at the forward end of the shaft 27 and at the rear 95 end of said shaft is the bevel-pinion 30 which engages the rack-segment 31 supported by the carriage 16.

Idle rollers 32 are carried by the housing 22 and said rollers engage opposite sides 100 of the guide-rail 33 on the frame 9. At the forward end of the guide-rail 33 is the switch 34 pivotally mounted at 35, and said switch is adapted to register with either one or the other of the curved guides 36, 105 according to the direction in which it is desired to swing the housing 2 whose rollers 32 may be directed into engagement with one or the other of the curved guides 36.

The furnace 37 is of the ordinary type 110

with the pots 38 arranged therein, and with openings 39, one opening for each two adjacent pots.

When my improved charging apparatus 5 is in use the hopper 8 having been charged from the bin 7, the trolley 2 is run onto the track 3, and by the electric crane the trolley is moved into position to charge a pair of pots as indicated in Fig. 1. When the 10 parts are in the position indicated in full lines Fig. 1, the ladle 29 is in position to receive the batch from the hopper 8, the outlet of the hopper being provided with a suitable gate for controlling the flow of the 15 batch. When the ladle has been filled with the batch the upper gate is closed and the motor 21 is started. This will advance the carriage 16, and as said carriage moves forward toward the furnace the ladle 29 20 proceeds to enter the furnace through the opening 39 in a straight line and when once through the door the ladle rises slightly, due to the fact that the wheels 17 advance up the inclined track portion 15, while the 25 wheels 18 descend the inclined portion 13 of the track 11. This slight raising of the ladle is continued until the ladle has passed the arch-stone 40 on its upward path, and then to avoid striking the edges of the pots 30 it is given a sharper rise by the action of the wheels on the inclined portions of the track 10 and 11 until it is high enough to pass over the tops of the pots. The ladle is now higher than the pots, but directly 35 between them and partly in front of them. As the carriage continues to advance the ladle still rises slightly and the rollers 32 on the housing 22 engage the switch 34 and are directed sidewise by said switch to one 40 of the curved guides 36. This deflection of the rollers 32 also deflects the ladle 29. The outer end of said shaft is deflected to a greater extent and the ladle is swung over the pot to be charged. At the same time the 45 pinion 30 moving in the rack-segment 31 turns the shaft about its axis, and the contents of the ladle is deposited into the pot.

The motor 21 is then reversed and the ladle rights itself and at the same time is 50 withdrawn from the furnace on the same path over which it entered, and is brought back again into position under the outlet of the hopper 8 to be filled again.

When one pot has been filled the switch 55 34 is reversed and the other pot filled in like manner. The apparatus is then moved to another opening in the furnace and the pots there are filled, and so on, until all the pots have been filled.

60 By my invention I provide a very simple and efficient form of apparatus for charging the pots in a glass melting furnace, the movement of the ladle from the filling position to the charging position being accurately controlled so that there is no lia-

bility of the ladle striking any part of the furnace. This accuracy of controlling enables me to use a charging opening in the furnace and providing for the charging of two pots from one small opening. Furthermore, the device can be operated with a minimum amount of labor and due to its 70 flexibility can be moved around without difficulty from one charging point to another. It is apparent that the handling of 75 the ladle may be manual labor where desired.

What I claim is:

1. In apparatus for charging glass furnace pots, the combination with a suitable 80 frame, of a batch supply receptacle carried thereby, a vertically undulating track on said frame, a carriage on said track, and a tiltable ladle mounted on said carriage whereby said ladle may be brought into position to receive the batch from said receptacle advanced into the furnace and lifted to avoid striking the edges of the pot and tilted to discharge the batch into said pot.

2. In apparatus for charging glass furnace pots, the combination with a suitable frame, of a batch supply receptacle carried thereby, a carriage, a tiltable horizontally swinging ladle mounted thereon adapted to be brought into position to receive the batch 90 from the receptacle, means for advancing said ladle in a straight vertical plane into the furnace, and means for further advancing said ladle when in the furnace and simultaneously therewith swinging the same 95 horizontally and tilting the same whereby the batch is discharged into one of said pots.

3. In apparatus for charging glass furnace pots, the combination with a suitable 105 frame, of a batch-supply receptacle carried thereby, vertical undulating-tracks on said frame, one above the other, a carriage mounted on said tracks, a horizontally swinging tiltable ladle mounted on said carriage, and means for tilting said ladle, whereby said ladle is brought into position to receive the batch from said receptacle advanced through the furnace opening, raised above the pots, swung into position and 110 tilted over one of said pots.

4. In apparatus for charging glass furnace pots, the combination with a suitable frame, of a batch-supplying receptacle carried thereby, vertical undulating-tracks on 120 said frame, a carriage on said tracks, means for driving said carriage, a horizontally swinging tiltable ladle mounted on said carriage, and means for swinging said ladle in either direction after it has entered the furnace, and means for simultaneously tilting 125 said ladle.

5. In apparatus for charging glass furnace pots, the combination with a suitable frame, of a batch-supply receptacle carried 130

thereby, tracks on said frame, a carriage mounted on said tracks, means for moving said carriage back and forth on said tracks, a housing swiveled to said carriage, a ladle 5 carried by said housing, a pinion on said housing, a rack-segment engaged by said pinion, and means for swinging said housing to one side or the other.

6. In apparatus for charging glass furnace pots, the combination with a suitable frame, of a batch-supply receptacle carried thereby, tracks on said frame, carriage mounted on said tracks, means for moving

said carriage to and fro thereon, a swiveled housing mounted on said carriage, a ladle 15 carried by said housing, diverging guides, a switch, a guide rail engaged by said housing whereby said housing may be directed by said switch to either one of said diverging guides.

20

In testimony whereof I, the said FRANK E. TROUTMAN, have hereunto set my hand.

FRANK E. TROUTMAN.
